UNITED STATES PATENT OFFICE

NEWELL C. PLATT, OF SPRINGFIELD, MASSACHUSETTS, ASSIGNOR TO UNDERWOOD ELLIOTT FISHER COMPANY, OF NEW YORK, N. Y., A CORPORATION OF DELAWARE

TYPEWRITING MACHINE

Application filed July 23, 1928. Serial No. 294,731.

This invention relates to manifolding typewriting or continuous billing machines where a succession of web-forms may be written, and each form, as it is written, be severed from the web by suitable means upon the machine.

The machine may have the well-known reciprocating carbon-carrier to hold carbons interleaved with the plies of the web, and a displaceable platen to allow the web to be straightened out for the carbons to be withdrawn from the written to a fresh section of the web. Before restoring the platen, the web is usually drawn forward by hand to engage a leading-edge gage, so as to bring the severing line to register with a usual severing knife, while the carbons may be stripped in opposite direction.

In cases where the web-plies are loosely superposed, and also in cases where the carbons extend near to the top edge of either a fan fold or a loose ply web, only a small edge-portion of the top of the web is left free of carbon. It is difficult or impossible for the operator to grasp the web at the top edge when gaging the same and stripping the carbons.

The invention therefore provides a self-releasing paper-clamp under the control of the operator, which will nip the narrow edge of the web above the carbons to hold the web at the carbon-stripping operation. This nipper is settable upon a gage-bar which usually forms the upward continuation of a front collating table and which is displaceable together with the platen in straightening out the carbons preparatory to stripping.

A finger-piece may be depressed to nip the paper, while releasing the finger-piece will release the paper.

Two superposed resilient paper-gripping open tongues are flatly arranged upon said gage-bar, said tongues normally spreading apart to receive therebetween the leading edge portion of the web. The device includes a body-portion slidable upon said gage-bar and provided with a set-screw, which tensions the lower tongue slightly against the gage-bar. A bevel face at the free end of

said tongue permits the leading edge of the web to slip from the gage-bar into the clamp. The tongue extends from said body-portion and does not exceed the width of the gage-bar, so that the operator's finger while pulling the web may slide along the gage-bar to be guided thereon until the leading edge abuts the gaging point. 55

A stud rises centrally from the tongue which lies against the gage-bar, said stud extending through a central opening in the other tongue. The projecting end of the stud has pivoted thereon a cam-member terminating in a finger-piece. It is so arranged that depression of the finger-piece will urge the adjacent resilient tongue to grip the edge of the paper, while releasing the finger-piece will allow the tongue to snap back to open position. 60

Said stud also furnishes the gaging point 70 for the leading edge of the web.

Other features and advantages will hereinafter appear.

In the accompanying drawings, 75 Figure 1 is a side elevation showing the paper gage or clamp in effective position upon the carriage of a fan-fold machine when the platen is displaced and the carbons about to be stripped.

Figure 2 is a similar view, with the platen restored and the clamp about to be released 80 in order to sever the gaged section of the web.

Figure 3 is an enlarged detail of the clamp-device, and shows more clearly the leading edge of the web in gaged position while indicating a relatively free small carbon-area of the web to be securely gripped by the clamp. 85

Figure 4 is a perspective detail of the clamp with parts drawn apart for a clear showing. 90

With reference to Figure 1, the carriage of a fan-fold machine includes the sides 10 of the carriage-frame which may be rigidly connected by the ordinary rear paper guide or apron 11. There are also indicated upon the carriage feed-rolls 12 to feed the paper around the platen. Attached to the rear of said paper-guide, by means of clips 13, are brackets 14 to carry pivoted thereon the 95 100

track-structure 15 which ordinarily supports a reciprocating carbon-carrier 16 shown in rearward position to abut a stop 17. Usual carbon-holding blades 18 are indicated upon the carrier to have attached thereon the rear ends of carbons 19 which are interleaved with plies 20 of a fan-fold web for continuous-billing operation. A rotary platen 21 is mounted in a swingable platen-frame 22 and shown in displaced position, the frame being swung upwardly about its shaft 23 mounted upon the sides of the platen-frame 22. At 24, 25, and 26 are indicated the well-known gears which transmit rotation from a platen-knob (not shown) to the platen 21. With the platen displaced for carbon-stripping purposes the web may pass straight through between the platen 21 and a usual web-severing knife 27 forming part of said swingable frame, and may continue straight over a front collating table 28 and a gage-bar 29 also mounted upon the platen-frame 22, to terminate between the tongues 30, 31 of the novel paper gage or clamp 32.

25 The clamp further includes a box-like body-portion or slide 33 upon which said tongues are fastened, as by rivets 34 (see Figure 4). The body-portion has slots 35 within which it receives said tongues and also receives the gage-bar 29 to be slidable thereon. A thumb-screw 36 is threaded into the rear of said body-portion and allows the clamp to be set upon the gage-bar as desired.

As the thumb-screw is tightened upon the gage-bar it will tension the resilient tongue 30 deflecting the same from its natural set indicated in dot and dash (see Figure 3). Since, moreover, the front edge of said tongue 30 is beveled off, it will allow the leading edge of the web to readily slip onto the tongue 30 and abut a stud 37 for a gaging point. The stud 37 is riveted upon the middle portion of the tongue 30 and rises through an opening 38 of the other tongue 31. A finger-piece 39 is stamped out of flat material and has ears or cams 40 by which with the aid of a pin 41 it is pivoted upon the free end of said stud 37. Due to its resiliency, the tongue 30 will engage upon the flat face 42 of the cams 40, thus holding the finger-piece 39 in raised, that is, ineffective position.

After the web is pulled forward to the gaging point, as in Figures 1 and 3, the finger-piece 39 may be depressed, urging the tongues to grip the leading edge of the web, a secure grip being insured by a rubber padding 43, which may be provided upon the front part of the tongue 31. A lug 44 is shown to be struck up from the body-portion 33, to serve as an abutment for the finger-piece 39.

The carbons are now free to be retracted and the platen to be restored from its Figure 1 to its Figure 2 position, when the operator's finger 40 may release the finger-piece 39 to allow the same to be urged back to inef-

tive position by the resilient tongue 31. The gaged section of the web may then be severed from the pack by tearing the same across the knife 27 in the usual manner, and the following section be written as indicated by a type-bar 45.

It will be noted that this combined gage and clamp is a unit structure that can be removed from the bar and laid aside without fear of the parts being lost; that the tongues 30 and 31, when secured together at one end to the slide 33, are formed to become tensioned open tongues at their free ends, ready to receive the leading end of the web between them; and that the compressed tongues are not locked in web-clamping position, but the finger is retained upon the depressed finger-piece until the carbons have been stripped, which makes the clamp semi-automatic.

Variations may be resorted to within the scope of the invention, and portions of the improvements may be used without others.

Having thus described my invention, I claim:

1. In a manifolding continuous billing machine, the combination with a carriage, a platen, a platen-frame, and means for retracting interleaved carbons from a written web-section, of a gage-bar extending upwardly from the front of the platen, means for gaging and holding the leading edge of the web preparatory to retracting the carbons, including a unit of two superposed tongues to receive therebetween the leading edge portion of the web, means whereby to adjust the unit up and down upon said gage-bar, a leading edge-gage in the form of a stud rising from the center portion of the lower tongue to extend through an opening in the upper tongue, and an actuating member pivoted upon the end of said stud and whereby to cause said tongues to grip the paper.

2. In a manifolding continuous billing machine, the combination with a carriage, a platen, a platen-frame, and means for retracting interleaved carbons from a written web-section, of a gage-bar extending upwardly from the front of the platen, means for gaging and holding the leading edge of the web preparatory to retracting the carbons, including a unit of two superposed open tongues to receive therebetween the leading edge portion of the web, means for adjusting the tongues up and down upon said gage-bar, and actuating means including a stud serving as a leading-edge gage and rising from the center portion of the lower tongue to extend through an opening in the upper tongue, and also including a finger-piece of flat material having lateral bent-over ears by which to embrace the end of said stud to be pivoted thereon, said ears to act as cams so that depression of the finger-piece will urge

130

the adjacent tongue to grip the leading edge portion of the paper.

3. In a manifolding continuous billing machine, the combination with a carriage, a platen, a platen-frame, and means for retracting interleaved carbons from a web-section, of a gage-bar extending upwardly from the front of the platen, means for gagging and holding the leading edge of the web preparatory to retracting the carbons, including a clamp having a body-portion and means by which to be adjustable up and down upon said gage-bar, two superposed tongues, extending from said body-portion to receive the leading edge of the web, the free end of the lower tongue, due to its resiliency, normally tensioned against the underlying gage-bar, so that the leading edge of the web may readily slip onto the tongue, and actuating means to cause the tongues to grip the paper.

NEWELL C. PLATT.
